UNITED STATES PATENT OFFICE.

ARCHER W. JOHNSON, OF HOLLAND, MICHIGAN.

SWITCH.

1,081,119.

Specification of Letters Patent.

Patented Dec. 9, 1913.

Application filed December 20, 1912. Serial No. 737,904.

To all whom it may concern:

Be it known that I, ARCHER W. JOHNSON, a citizen of the United States, residing at Holland, in the county of Ottawa and State 5 of Michigan, have invented new and useful Improvements in Switches, of which the following is a specification.

This invention relates to improvements in switches and has particular application to a 10 multiple-gap switch.

In carrying out the present invention, it is my purpose to provide a multiple break switch whereby an electric circuit may be opened and closed and which when operated 15 to open and close the circuit will make and break respectively the circuit at a plurality of points so as to eliminate arcing or sparking at the contacts.

It is also my purpose to provide a switch 20 of the type set forth wherein the contacts and blades will be constructed in such manner as to enable the circuit to be made and broken quickly and whereby, owing to the number of blades and coöperating contacts 25 and the construction thereof, arcing will be eliminated in the breaking of the circuit.

Furthermore, I aim to provide a multiple break switch which will embrace the desired features of simplicity, efficiency and durability and which may be manufactured and marketed at a relatively low cost and installed in an electric circuit with ease and facility.

With the above and other objects in view, 35 the invention consists in the construction, combination and arrangement of parts hereinafter set forth in and falling within the scope of the claim.

In the accompanying drawing, Figure 1 40 is a plan view of an electric switch constructed in accordance with my present invention, the casing being removed. Fig. 2 is a transverse sectional view through the casing, the switch elements being shown in 45 elevation. Fig. 3 is a cross sectional view through one of the blades of the movable switch element, and Fig. 4 is a view in elevation of the contacts.

My improved switch is especially designed 50 for use at interurban trolley car stations where, by the use of a signal such, for instance, as a lamp, the motorman of a car is advised of the presence of a passenger at the station so that he may bring his car to a 55 standstill. In view of the high voltage or

high tension currents, employed on interurban trolley lines, it is practically impossible to use a single break switch as the arcing or sparking at the contacts in the breaking of a signal circuit is detrimental to the 60 switch. By means of my invention, the signal circuit is made and broken at a plurality of points simultaneously and thus the sparking and the bad effects arising therefrom are eliminated.

Referring now to the accompanying drawing in detail, the numeral 1 indicates the base of the switch, said base being constructed of suitable insulating material and, in the present instance, is of rectangular contour. Suitably secured to the base 1 adjacent to one longitudinal edge thereof are a plurality of pairs of contacts, the contacts of each pair being formed of metallic strips 2, 2 each having one end bent upon itself 75 and fastened to the base, while the opposite ends thereof diverge outwardly as at 3, 3 to form a substantially V-shape contact 4. Mounted upon the base 1 at the opposite sides of the pairs of contacts and electrically connected with such contacts are binding posts 5, 5 whereby the switch may be connected in an electric circuit. Appropriately fastened to the base and extending outwardly therefrom and spaced apart are 80 pivot lugs 6, 6 disposed adjacent to the longitudinal edge of the base opposite from the sets of contacts and formed with alining apertures through which is passed a pivot rod 7 secured to a block 8 composed of suitable insulating material and carrying a plurality of switch blades 9 projecting outwardly from one edge of the block and spaced apart distances equal to the distance between the pairs of contacts. Each 85 blade 9, as clearly illustrated in Fig. 3, is of V-shape in cross section and is adapted to engage the V-shape contacts formed by the outwardly diverging pairs 3, 3 of the respective pair of strips 2, 2 so as to bridge such 90 strips and close the electric circuit.

By means of the construction just described, it will be seen that when the block 8 is swung about the pivot point, the switch blades 9 will simultaneously engage the 105 pairs of contacts and so close a plurality of breaks in the electric circuit. On the other hand, when the circuit is broken or opened, it will be seen that the switch blades 9 simultaneously leave the contacts and so 110

break the circuit at a number of points thereby minimizing arcing or sparking at the contacts.

In the present instance, the movable element of the switch composed of the block 8 and the switch blades 9 is adapted to be normally disengaged from the contacts so that the electric circuit is normally open. For this purpose, in the present embodiment of my invention, substantially U-shaped leaf springs 10, 10 each have one limb bearing upon the base while the opposite limb thereof engages the pin 11 extending outwardly from the respective side edge of the block 8. Thus, the springs 10, 10 hold the switch normally open. In order to close the switch, I employ a push button 12 formed with a head 13 slidably disposed within a recess 14 formed in a casing or cover 15 adapted to inclose the switch, while extending from one side of the head 13 is a shank 16 slidably disposed within an opening 17 formed in the wall of the casing 15 coaxial with the depression or recess 14 therein, the shank 16 carrying an eye bolt 18 having the eye portion thereof pivoted within a recess formed in the block 8. Thus, when the push button 12 is pressed, the switch is closed and remains closed so long as the push button is influenced. If, however, the push button is released, the springs 10, 10 act to open the switch.

From the foregoing description taken in connection with the accompanying drawing, the construction, mode of operation and manner of employing my invention will be readily apparent. It will be seen that I have provided a multiple break switch whereby an electric circuit may be closed for signaling purposes and is automatically opened at a plurality of points subsequent

to the closing thereof, thereby eliminating sparking and maintaining the controlled circuit normally open.

While I have herein shown and described one preferred form of my invention by way of illustration, I desire to have it understood that I do not limit myself to the precise details of construction herein described and delineated, as modification and variation may be made within the scope of the claim and without departing from the spirit of the invention.

I claim:

A circuit closer comprising a base, a plurality of pairs of contacts upstanding from the base adjacent to one longitudinal edge thereof, pivot lugs on the base adjacent to the opposite longitudinal edge thereof, a block pivotally mounted within said lugs, a plurality of blades carried by said block and extending outwardly from one edge thereof and spaced apart, said blades co-operating with said contacts, a casing inclosing said blades and contacts and formed with a depression in the top wall thereof and an opening in the bottom wall of the depression, a button slidably mounted within the depression, a shank on said button and extending through the opening, a connection between said shank and block whereby upon the depression of the button, the block will be moved to circuit closing position, and springs holding said blocks normally in circuit opening position.

In testimony whereof I affix my signature in presence of two witnesses.

ARCHER W. JOHNSON.
